UNITED STATES PATENT OFFICE.

IRA W. NONNEMAN, OF WARREN, OHIO, ASSIGNOR TO THE BORDEN COMPANY, OF WARREN, OHIO, A CORPORATION OF OHIO.

DIESTOCK.

1,404,996

Specification of Letters Patent. Patented Jan. 31, 1922.

Application filed February 9, 1920. Serial No. 357,234.

To all whom it may concern:

Be it known that I, IRA W. NONNEMAN, a citizen of the United States, residing at Warren, in the county of Trumbull and State of Ohio, have invented a certain new and useful Improvement in Diestocks, of which the following is a full, clear, and exact description, reference being had to the accompanying drawings.

10 This invention relates to a die stock and is particularly concerned with that type of die stocks in which the guiding frame is clamped to the pipe, and has a threaded engagement with the chaser carrying frame

15 to insure accurate advancement of the chasers along the pipe, cam projections extending from the guide frame past the chasers, serving to govern the recedence thereof.

20 The objects of the present invention include the provision of a simple effective construction; the provision of adjusting means for moving the chasers inwardly and outwardly with relation to the pipe to be 25 threaded to accomplish accurate cutting of the threads to exact standard size or over and undersized threads as desired.

Still another object is the provision of a gear and screw device for causing simultaneous adjustment of the chasers.

A preferred embodiment of my invention is illustrated in the accompanying drawings in which Fig. 1 is a face or front view of my die stock; Fig. 2 is a side elevation partially in section; Fig. 3 is a face view of an adjusting cam plate for the guiding frame; Fig. 4 is a view similar to Fig. 1 with the retaining plate and gear member removed; Fig. 5 is a detail perspective of one of the 35 chasers; Figs. 6 and 7 are details of yokes each adapted to engage two chasers and threaded to receive adjusting screws; Fig. 8 is an inner face view of the gear plate for actuating the adjusting screws; Fig. 9 is an 40 enlarged sectional detail through a portion of the frame showing the adjusting screws, gear plate and receding cams.

The chaser carrying frame is shown as comprising a central sleeve 1 and radial web 50 2 integral with flanges 3 and 4 from which project outwardly extending sockets 5 to receive the usual die stock handles 6.

The forward portion of the sleeve 1 and the flange 3 are provided with radial slots

or openings adapted to receive chasers 10, 55 each of which has a transverse notch 12 to receive a yoke or bridge member 15. These yokes are shown as extending partially around the central sleeve 1 and then across the chasers at right angles thereto and as 60 having their ends slidably engaging parallel guide flanges 14 on each chaser frame. Intermediate of the legs of each yoke is provided a boss 20 internally threaded to receive screws 21, projecting outwardly 65 through and in slidable and rotatable engagement with the sleeve 1 and extending into openings through the sockets 5.

The outer ends of the screws 21 are provided with toothed pinions 22 engaging 70 teeth 23 forming a face gear on an annular plate 25 rotatably embracing the sleeve 1 outside of the chasers and yokes. On this plate 25 are forward projections 26 for conveniently rotating the plate. This rotation 75 causes corresponding rotation of each of the screws 21 resulting in inward or outward movement of the yokes 15, thus moving the chasers correspondingly.

This guiding plate is held in its rotatable 80 engagement with the chaser carrying frame and with the gear teeth 23 engaging the pinions 22 by means of a nut 35 threaded on a forward extension of the sleeve 1 and provided with wings 36 for convenience 85 in adjusting this nut. This nut also serves to clamp or lock the plate against the flange 3.

Projecting through the openings 8 in the 90 sockets 5 are cam fingers 30 against which the ends of the screws 21 may abut. These cam fingers are shown as having their inner surfaces 31 tapered outwardly rearwardly of the die stock while the fingers are rigidly carried by outward projections on a ring 33 95 rotatably embracing an annular groove formed by shoulders on the guiding frame 40 and a retaining nut 41, thus rotation of the ring and cam fingers with relation to the guiding frame is permitted, but the fingers and ring are prevented from longitudinal movement with relation to this frame and are thereby caused to move through the chaser carrying frame as the threading progresses. The outer ends of the cam fingers 100 32 are provided with overhanging shoulders 33 adapted to engage the periphery of the gear plate 25 to serve as a stop for the out-

105

ward movement of the chaser carrying frame relative to the guiding frame.

To cause relative movement of the chaser frame and guiding frame and to insure the accurate progress of the chasers during the thread cutting operation, I provide master screw threads on the rearward portion of the sleeve 1 engaging internal threads at 43 on the guiding frame. These screw threads 10 have a pitch corresponding to the thread to be cut by the chasers 10.

The guiding frame is preferably in the nature of a sleeve, portions of which are cut away for lightness, and having enlargements 15 45 forming radial guides for clamping jaws 46. Rotatably mounted on the frame is a cam plate 47 having eccentric cam slots or grooves 48 adapted to engage pins 49 rigid with the jaws 46 whereby the turning of the 20 plate 47 moves the gripping jaws inwardly or outwardly. The periphery of the plate 47 may be knurled if desired or for convenience may have an outwardly projecting wing 50 for rotating it with relation to the 25 frame to cause the gripping jaws to engage or release the pipe or other article being threaded. When brought into engagement with the pipe the clamping may be made more firm by use of a screw as indicated at 30 52 extending through one of the jaws and provided with a pivoted handle 53 whereby the gripping on the pipe may be tightened effectively.

In use the operation of my die stock is as 35 follows:

Assume that the gripping jaws of the guiding frame have been clamped onto a pipe and the set screw 52 tightened, the chasers are now adjusted to cut the thread of the 40 exact diameter desired by relieving the locking and retaining nut 35 and turning the plate 25. This rotates the screws 21 moving the yokes inwardly or outwardly as desired. The nut 35 is again tightened to clamp the 45 plate against rotation, thus locking the yokes and chasers in the position given them, and the threading operation may proceed. As the chaser carrying frame moves toward the guiding frame, under the influence of the 50 threaded connection between them, the screws 21 move along the tapered surfaces 31 of the cam fingers which allows these screws to slide outwardly with the yokes and chasers, thus tapering the thread being cut. 55 It will be noted that the yokes 15 have the legs engaging the chasers at right angles thereto and the outward thrust of the chasers is received at three points, namely: the ends of the yokes, bearing against guides 14, 60 and the screw 21 bearing against the cam fingers 30.

I claim:

1. In a die stock, the combination of a chaser carrying frame, bridge members extending across a plurality of chasers and

means for adjusting said bridge members inwardly and outwardly, means on the chaser carrying frame for simultaneously actuating said means, and variable abutments engaging the adjusting means for controlling the recession of the chasers. 70

2. In a die stock, the combination of a chaser carrying frame, bridge members extending across a plurality of chasers and means for adjusting said bridge members inwardly and outwardly including screws engaging the bridge members and inclined abutments engaging the screws for controlling the recession of the chasers and a revoluble member on the chaser carrying frame 75 for simultaneously rotating said screws. 80

3. In a die stock, the combination of a chaser carrying frame, bridge members each extending across a plurality of chasers and having a guiding engagement with the frame at a plurality of points to receive the outward thrust of the chasers, an adjusting element on each bridge member and a member carried by the frame for actuating 85 said adjusting elements. 90

4. In a die stock, the combination of a chaser carrying frame, bridge members each extending across a plurality of chasers and having an engagement to receive the outward thrust of the chasers, screws engaging 95 the bridge members and a revoluble plate carried by the frame and having an inwardly facing annular external gear in engagement with pinions on said screws for rotating them to adjust the chasers. 100

5. In a die stock, the combination of a chaser carrying frame, yokes each engaging two chasers, a screw engaging each yoke intermediate of its chasers, cam surfaces controlling recession of the chasers by abutting the outer ends of the screws, a revoluble gear member carried by the chaser frame, pinions rigid with said screws and engaged by said gear member, said pinions and said gear member having a relative radial movement. 105 110

6. In a die stock, the combination of a chaser carrying frame, yokes each engaging a plurality of chasers, a screw engaging each yoke intermediate of its chasers, cam surfaces movable relative to said frame for controlling a recession of the chasers by abutting the outer ends of the screws, a revoluble gear member journaled on a sleeve extension of the frame, a ring screwing onto said extension for clamping the gear member, and pinions rigid with said screws and engaged by said gear member. 115 120

7. In a die stock, the combination of a chaser carrying frame having substantially concentric walls spaced apart, chasers mounted to slide radially, each in the two walls, a yoke between the walls engaging the chasers, a screw journaled in the outer wall and engaging the yoke, an inwardly facing gear 125 130

rotatably mounted on the inner wall, and a pinion on the screw meshing with the gear.

8. In a die stock, the combination of a frame having inner and outer substantially concentric walls spaced apart, radial chasers mounted in said walls, a yoke between the walls engaging a plurality of chasers, a screw journaled in the outer wall and engaging the yoke, an inclined abutment beyond the outer wall engaging the screw to control recession of the chasers, and a rotative annular gear meshing with a pinion on the screw.

9. In a die stock, the combination with a frame, of two chasers therein, a bridge member engaging said chasers and having also a guiding engagement with the frame at a plurality of points in the vicinity of the chasers, an adjusting screw connected with the bridge member, a pinion on said screw,

and a member having gear teeth meshing with the pinion for adjusting the screw.

10. In a die stock, the combination of a frame, a pair of chasers slidably mounted therein, a bridge member extending across said chasers and having a sliding engagement beyond the chasers with surfaces on the frame which are parallel to each other, an adjusting screw mounted in the frame and having a threaded engagement with the bridge member, an inclined abutment slidably engaging the screw to control the recession of the chasers, a pinion on the screw, and a plate rotatably mounted on the frame and having an inwardly facing annular gear engaging said pinion.

In testimony whereof, I hereunto affix my signature.

IRA W. NONNEMAN.
